UNITED STATES PATENT OFFICE.

GRANVILLE E. PALMER, OF BOSTON, MASSACHUSETTS, ASSIGNOR TO THE PALMER ELECTRIC & MANUFACTURING COMPANY, OF BOSTON, MASSACHUSETTS, A CORPORATION OF MAINE.

ALTERNATING-CURRENT ELECTROMAGNET.

1,343,404.

Specification of Letters Patent. Patented June 15, 1920.

Application filed December 10, 1918. Serial No. 266,132.

To all whom it may concern:

Be it known that I, GRANVILLE E. PALMER, a citizen of the United States, residing at Boston, in the county of Suffolk and State of Massachusetts, have invented new and useful Improvements in Alternating-Current Electromagnets, of which the following is a specification.

This invention has reference to electromagnets for use in single-phase alternating-current circuits, the object of the invention being to provide a magnet which produces no chattering or hum and in which the armature is suddenly released when the potential drops below a predetermined point.

On the accompanying drawings,—

Figure 1 represents in front elevation a magnet embodying the invention.

Fig. 2 represents a side elevation of the same.

Fig. 3 represents a front elevation partially in section.

Considered as an entirety, the magnet comprises two parallel solenoids 10, 11, arranged in series in a single-phase alternating current circuit. As illustrated, these solenoids are secured by brackets 12 and 13 to a suitable upright base or support 14. Coöperating with the solenoids or coils 10, 11, are two plungers 15, 16, respectively, which are of course parallel and which project upwardly from a cross bar 17, secured thereto or integral therewith, into the spools 35 of said solenoids. The plungers 15, 16, and cross bar 17 form a U-shaped member *a*. When a single-phase alternating circuit of sufficient voltage is supplied to the coils 10, 11, the U-shaped member is raised, as naturally would be expected, to approximately the position shown in Fig. 3. In conjunction with the member *a*, I provide an oppositely arranged supplemental U-shaped member *b*, which comprises a cross bar 19 and parallel plungers 20, the latter extending downwardly into the spools 21 of the coils and being provided with flat end portions 22 to make contact with the ends of the plungers 15, 16, when the latter are in elevated position. Under normal condi-

tions, when the solenoids are deenergized, the upper member rests loosely upon a support afforded by the upper portion of the solenoids, with the plungers 20 extending downwardly toward the middle portion of 55 said solenoids, and the lower member is at the lower limit of its movement with its plungers separated from those of the upper member, all as shown in Fig. 1. When a single-phase alternating current of not less 60 than predetermined potential is supplied to the solenoids, the lower armature member is drawn upwardly and the magnetic force tends to draw the upper armature member down into the solenoids, which is, of course, 65 resisted by the stationary portion of the solenoid upon which the upper member rests. The magnetic mass of the lower member is so proportioned to that of the upper member that under the condition recited the latter is lifted from its support 70 by the lower member, and the two members, with their ends in contact, float in the magnetic field, a magnetic circuit being completed through the armature.

In order that the upper member 18 may not be displaced mechanically, I employ any suitable guide or holder therefor. One, comprising a U-shaped strap 23, may be employed, which bridges the cross bar 19 80 but which is of such dimensions as not to interfere with the free movement of the upper member and not to make mechanical contact therewith when the latter is floating.

I have observed (and it is a characteristic of the magnet which I have described) that, when the coils are excited by a current of the desired given potential and the armature is floating in the magnetic field, no 90 hum or chattering can be detected. If the potential is gradually lowered, the armature drops until the upper member rests upon its support, whereupon a chattering or hum is heard. The parts remain in this 95 position during the continued gradual lowering of potential in the exciting circuit until a certain minimum voltage is reached, whereupon the lower solenoid is suddenly released and drops. This is doubtless due 100

to the fact that the **U**-shaped alternately-disposed members are mutually attracted magnetically, and remain in contact until the loss of potential in the exciting circuit 5 is sufficient to enable the weight or mass of the lower member to overcome the mutual magnetic attraction and cause its sudden release.

Considered in one aspect, the upper and 10 the lower members comprise a two-part bodily movable armature, the members of which are separable when the current in the solenoids fails, and which furnish a complete magnetic circuit or field when the solenoids are energized. Thus, considering the 15 two parts of the armature as complements of a whole, I have provided what I may term a floating armature in which there is a complete magnetic circuit. From another 20 aspect, the lower member may be considered as the main armature, and the upper member as a supplemental and magnetic-field-completing armature.

I may utilize the magnet which I have 25 herein described for a variety of purposes which will be apparent to persons skilled in the art. For example, I may use it for opening or closing a circuit, which includes stationary spring contacts 24, 24, mounted 30 upon the base 14. The cross bar 17 of the lower armature member is provided with a movable contact 25, which, when the solenoids are excited, engages the spring contacts 24 to close the circuit therethrough. 35 I may also use the lower member to accomplish other work, by its acquired momentum after being released on failure of current in the solenoids.

As a matter of detail, the lower member 40 may be guided in its movements by a vertical diamagnetic pin 26 depending from the bracket 12 and passing through an aperture in the cross bar 17. Stops 27 are also located in the path of the lower armature 45 to arrest its downward movement, as shown.

Care should be taken in the construction of the two-part armature, comprising the two **U**-shaped opposing members, so to relate their masses that, when the alternating 50 current of the desired maximum potential is passing through the solenoid coils, the opposing forces exerted upon said members will permit them to maintain a substantially stabilized floating position in the 55 magnetic field out of mechanical contact with any parts against which they might vibrate and produce a hum or chatter.

Having thus explained the nature of my 60 said invention and described a way of making and using the same, although without attempting to set forth all of the forms in which it may be made or all of the modes of its use, what I claim is:—

1. An alternating-current electromagnet, 65 comprising a pair of solenoids, and an ar-

mature therefor consisting of separable oppositely arranged movable **U**-shaped members which, when the solenoids are energized, furnish a closed magnetic field, and are mechanically disconnected from all stationary portions of the electromagnet. 70

2. An alternating-current electromagnet, comprising a pair of solenoids, and opposing movable armature members common to both solenoids but physically disconnected 75 therefrom, whereby, when the solenoids are energized, the armature members float in the magnetic field.

3. An alternating-current electromagnet, comprising a pair of upright solenoids, and 80 opposing movable **U**-shaped armature members common to and extending into the opposite ends of both said solenoids.

4. An alternating-current electromagnet, comprising a pair of solenoids, and an un- 85 attached two-part armature common to both solenoids, extending into both ends of the solenoids and furnishing a closed magnetic circuit and floating freely in the magnetic field of said solenoids when the latter are 90 energized.

5. An alternating-current magnet, comprising a pair of solenoids, and an armature consisting of normally-separated opposing bodily-movable members arranged in the 95 magnetic field thereof, and each bodily movable toward the other into contact therewith when the solenoids are energized, thereby forming a closed magnetic circuit, said armature, when said solenoids are 100 energized, freely floating in the magnetic field thereof, without physical connection with any stationary part of the magnet.

6. An alternating-current magnet, comprising a pair of solenoids, and an armature 105 consisting of oppositely arranged bodily-movable **U**-shaped members common to both solenoids and having plungers projecting into opposite ends thereof.

7. An alternating-current magnet, comprising a pair of solenoids, and an armature consisting of oppositely arranged bodily-movable **U**-shaped members common to both solenoids and having plungers projecting into opposite ends thereof, said 110 members being proportioned, as to magnetic mass, to cause one of said members to displace the other bodily when said solenoids are energized.

8. An alternating-current magnet, comprising a pair of solenoids arranged in parallelism, and an armature consisting of a pair of bodily-movable separable **U**-shaped members arranged to make contact with each other between the ends of the solenoids 115 to float freely in the magnetic field of the solenoids.

9. An alternating-current magnet, comprising a pair of solenoids and an armature common to both solenoids, floating in the 120

magnetic field thereof and forming a closed magnetic circuit.

10. An alternating-current magnet, comprising a pair of vertical solenoids, a main armature therefor common to both solenoids and having plungers movable upwardly into said solenoids, and a bodily-movable

supplemental movable armature above and common to both solenoids and having plungers extending downwardly into said solenoids. 10

In testimony whereof I have affixed my signature.

GRANVILLE E. PALMER.
